CLARENCE S. SNAVELY AND MAX FUNCKE, OF PITTSBURGH, PENNSYLVANIA, AS-SIGNORS TO THE UNION SWITCH & SIGNAL COMPANY, OF SWISSVALE, PENNSYLVANIA, A CORPORATION OF PENNSYLVANIA.

ELECTRICAL-CONTACT STRUCTURE.

Application filed June 4, 1925. Serial No. 34,859.

Our invention relates to electrical contact structures and is particularly suitable for, though in no way limited to, use in electrical relays such as railway signaling relays.

We will describe one form of electrical contact structure embodying our invention and will then point out the novel features thereof in claims.

10 In the accompanying drawing, Fig. 1 is a view showing, in elevation, one form of relay provided with a contact structure embodying our invention. Fig. 2 is an exploded view, showing, in perspective, the contact structure illustrated in Fig. 1. Fig. 15 3 is a vertical sectional view of the strap 21.

Similar reference characters refer to similar parts in each of the several views.

Referring first to Fig. 1, the reference character A designates the top plate of a relay. This plate is made of some suitable insulating material and carries an electromagnet B. The cores 1 of this magnet, only one of which is shown in the drawing, pass through the plate A and terminate, on the underside of the plate, in pole faces 2. Secured to the pole faces 2 by screws 4 is a bracket 3. An armature 6 of magnetizable material such as soft iron is pivotally supported on an axis 5 carried by bracket 3, and is arranged to be drawn upwardly toward pole faces 2 when magnet B is energized. Attached to the underside of armature 6 is a Z-shaped supporting member 7 of insulating material such as porcelain, which in turn carries a flat contact finger 8. When magnet B is de-energized the armature 6 drops down under the influence of gravity, and finger 8 then engages a back contact 9 which is fastened to top plate A by a binding post 10. When magnet B is energized, however, armature 6 is drawn upwardly into engagement with spacing pin 25 in the pole faces 2, and contact finger 8 then engages a front contact post D, attached to top plate A.

Referring now also to Figs. 2 and 3, the contact post D comprises a holder 12 of ap-

proximately the shape of an inverted U. The top of this holder is provided with a U-shaped slot 13 which receives the shank 11^a of a terminal bolt 11 which bolt passes through the top plate A. The bolt 11 has a square head 11^b which is prevented from rotating by the sides of the holder 12. The lower ends of the holder 12 constitute two spaced parallel plates 14 and 15 provided with registering elongated openings 14^a and 15^a, respectively. A flat contact block 18, preferably of graphite, is interposed between the plates 14 and 15 of holder 12. This contact block is substantially rectangular in shape and has a rounded lower contact surface 20. A screw 17 passes through openings 14^a and 15^a in the plates of holder 12 and also through a hole 19 in block 18. The hole 19 is of such size as to make a snug fit with the screw 17. A strap 21 (see Fig. 3) having ears 22 which overlap the vertical edges of block 18, is threaded at 23 to receive the end of screw 17. When the block 18 is placed between the plates 14 and 15, and the screw 17 is turned up in the strap 21, the block is clamped firmly in place. The ears 22 prevent rotation of the block about screw 17. The outer surface of plate 15 is provided with a series of parallel teeth 16 and the inner surface of strap 21 is provided with a series of similar teeth 24, the teeth on the two parts being arranged to fit together to prevent relative motion of the strap and the holder should the screw 17 become slightly loosened.

It will be seen that the screw 17 enters the hole 19 in block 18 with a snug fit, but enters the openings 14^a and 15^a with considerable vertical clearance. By loosening the screw 17 slightly to disengage the teeth on plate 15 and strap 21, and moving the strap and screw up or down with respect to the holder, the block 18 will be moved correspondingly. The block may be clamped in the new position by drawing up on the screw. It is therefore possible to adjust the position of the block with respect to the holder, and hence the exact location of the contact sur-

face 20 with which the finger 8 engages, may be accurately and conveniently adjusted.

One advantage of our invention is that all of the adjustments are made at the contact post D and therefore the contact finger 8 need not be bent to make proper adjustments.

Another advantage is that, because of the interfitting teeth 16 and 24, a slight loosening of the screw 17 will not permit the block to move in the support 12 and thereby destroy the adjustment of the contact structure.

Still another advantage of our invention is that the graphite block 18 has a form which is easily and cheaply machined, there being no surfaces which must be very accurately dressed. By making the block 18 flat, considerable pressure may be exerted on the block by screw 17 to insure good electrical contact without danger of fracturing the block.

In addition to these advantages it should be mentioned that all of the parts except the block 18 may be cheaply prepared by punching without the necessity of expensive machining operations.

Although we have herein shown and described only one form of electrical contact structure embodying our invention, it is understood that various changes and modifications may be made therein within the scope of the appended claims without departing from the spirit and scope of our invention.

Having thus described our invention, what we claim is:

1. In combination, an electrical contact structure for co-operation with a movable contact finger, said structure comprising a holder having spaced parallel plates provided with registering elongated openings, a screw passing through said openings, and a contact block having a hole to accommodate said screw with a tight fit, and clamped between said plates by said screw, said openings being elongated in such direction as to permit adjustment of the contact block toward and away from the contacting surface of said movable contact finger.

2. In combination, an electrical contact structure for co-operation with a movable contact finger, said structure comprising a holder having spaced parallel plates, a flat contact block located between said plates, and a screw passing through said plates and said block for clamping the block in adjusted position toward and away from the contacting surface of said finger.

3. In combination, a holder having spaced parallel plates, a flat contact block between said plates, a screw passing through said plates, and a strap having a threaded hole to receive the end of said screw for clamping

the block in adjusted position with respect to said holder.

4. In combination, a holder having spaced parallel plates, a strap in contact with the outer face of one said plate, the strap and said plate being provided with interfitting teeth, a flat contact block between said plates, and a screw passing through said plates and said block and threaded in said strap for clamping said block in adjusted position with respect to said holder.

5. In combination, a fixed top plate, a terminal bolt in said top plate having a square head, a holder having a flat top provided with a U-shaped slot to embrace the shank of said bolt and bent to engage the sides of the square head, two parallel plates on said holder provided with registering elongated openings, a screw passing through said openings, a strap threaded to receive the end of the screw whereby the strap is drawn against the outer face of one said plate, the outer face of said one plate and the inner face of said strap being provided with a plurality of interfitting teeth, and a contact block clamped between said plates and having a hole to receive said screw with a snug fit.

6. In combination, a holder having spaced parallel plates, a contact block of the same width as said plates and interposed therebetween, a strap in contact with one said plate and having ears bent to engage the edges of said block, and a screw passing through said two plates and said block and threaded in said strap to clamp the block in adjusted position with respect to said holder.

7. In combination, a holder having spaced parallel plates, a flat substantially rectangular contact block interposed between said plates and clamping means passing through said plates with considerable clearance and through said block with a snug fit.

8. In combination, a holder having spaced parallel plates provided with registering elongated openings, a contact block between said plates, a screw passing through said block with a snug fit and also passing through said openings, and a strap threaded to receive said screw and cooperating therewith to clamp the block between said plates.

9. In combination, a holder having spaced parallel plates provided with registering elongated openings, a contact block between said plates, a screw passing through said block with a snug fit and also passing through said openings, and a strap threaded to receive said screw and cooperating therewith to clamp the block between said plates, one of said plates and the strap being provided with interfitting teeth to prevent accidental motion of the strap.

10. In combination, a holder having two spaced parallel plates provided with registering elongated openings, a screw passing

through said openings, a strap threaded to screw with considerable clearance, the strap receive the end of the screw whereby the having ears bent to engage the sides of said 10 strap is drawn against the outer face of one block.
said plate, the outer face of said one plate In testimony whereof we affix our signatures.
5 and the inner face of said strap being provided with a plurality of interfitting teeth, and a contact block clamped between said plates and having a hole to receive said

CLARENCE S. SNAVELY,
